UNITED STATES PATENT OFFICE

1,966,860

SIGNALING DEVICE

Joseph W. Hughes, New Kensington, Pa.

Application August 19, 1933, Serial No. 685,930

2 Claims. (Cl. 88—1)

This invention relates to a signaling device and has relation more particularly to a device for use in traffic, and it is an object of the invention to provide a signal adapted to be placed upon the hand of a person in a manner whereby when the hand is extended the signal can be readily observed by the driver of a following car either during the daytime or after nightfall.

Another object of the invention is to provide a device of this kind constructed in a manner whereby it may be worn on the hand with comfort and also wherein means are provided to facilitate the desired maintenance of the device in applied position.

15 The invention consists in the details of construction and in the combination and arrangement of the several parts of my improved signaling device whereby certain important advantages are attained and the device rendered simpler, less expensive and otherwise more convenient and advantageous for use, as will be hereinafter more fully set forth.

The novel features of my invention will hereinafter be definitely claimed.

25 In order that my invention may be the better understood, I will now proceed to describe the same with reference to the accompanying drawing, wherein:—

Figure 1 is a view in top plan of a signal constructed in accordance with an embodiment of my invention;

Figure 2 is a sectional view taken substantially on the line 2—2 of Figure 1 looking in the direction of the arrow;

35 Figure 3 is a fragmentary view in rear plan of the device as illustrated in Figure 1;

Figure 4 is an enlarged fragmentary detailed sectional view taken substantially on the line 4—4 of Figure 1.

40 As herein disclosed, my improved signal comprises a relatively large crystal 1 preferably red in color and which is of a material to readily reflect the rays of light, either natural or artificial, that may be imposed thereon. The 45 rear face of this crystal 1 is flat and has close contact with a metal plate 2 preferably of aluminum which serves as a medium to reduce the glare of the crystal 1 whereby the efficiency of the device as a signal is materially facilitated.

50 The marginal portion of this plate 2 is provided with a reverted flange 3 which is disposed on an inward incline for close and firm contact with the applied crystal 1 whereby said crystal is effectively held in applied position with respect 55 to the plate 2. The rear face of the plate 2

has imposed thereover a pad 4 of desired material but preferably of a yielding or deformable character such as felt, soft rubber and the like.

The plate 2 outwardly of the reverted flange 3 is returned, as at 5, for clinching engagement 60 with the marginal portion of the pad 4 whereby said pad 4 is maintained in desired assembly in the device. It is to be particularly noted that the plate 2 provides means for holding the crystal 1 and the pad 4 in desired unitary assembly with the plate 2.

At diametrically opposed points the plate 2 outwardly of the reverted flange 3 is provided therethrough with the slots 6. These slots 6 are continued through the adjacent portions of 70 the applied pad 4 and are through the clinching marginal portion of the plate 2. Engaged through these slots 6 are the loops 7, one of which being carried by an elastic tab 8 and another by an elongated elastic strap 9. The 75 tab 8 carries a buckle 10 of any desired type with which the free end portion of the strap 9 is adapted to coact thus providing convenient adjustable connection between the tab 8 and the strap 9 to allow the device to be effectively 80 held to the back of the hand of a person. Of course, if preferred, the device could be applied with the jewel over lying the palm side of the hand. The crystal 1 is to be of any desired material having the requisite reflective properties.

With a signal as herein disclosed applied upon the hand of a driver or other occupant of a vehicle, the driver of a following car will be able to readily discern the desired signal on an extended hand either during the daytime or after night fall and more particularly the latter as the light beam from the headlights of the following car will be effectively reflected by the crystal 1 on the extended hand.

95 From the foregoing description it is thought to be obvious that a signaling device constructed in accordance with my invention is particularly well adapted for use by reason of the convenience and facility with which it may be assembled and operated, and it will also be obvious that my invention is susceptible of some change and modification without departing from the principles and spirit thereof and for this reason I do not 100 wish to be understood as limiting myself to the precise arrangement and formation of the several parts herein shown in carrying out my invention in practice except as hereinafter 105 claimed.

I claim:—

1. A traffic signal comprising a crystal, a plate overlying the back of the crystal and having a reverted flange in close contact with the applied crystal to hold said crystal to the plate, a pad disposed over the back face of the plate, the marginal portion of the plate outwardly of the reverted flange being returned for clinching engagement with the marginal portion of the pad, said plate at substantially diametrically opposed points and outwardly of the reverted flange being provided with openings, said openings being through the clinching portion of the plate, and hand encircling straps having extremities secured to the plate through said openings.

2. A traffic signal comprising a crystal, a plate overlying the back of the crystal and having a reverted flange in close contact with the applied crystal to hold said crystal to the plate, a pad disposed over the back face of the plate, the marginal portion of the plate outwardly of the reverted flange being returned for clinching engagement with the marginal portion of the pad, said plate at substantially diametrically opposed points and outwardly of the reverted flange being provided with openings, and hand encircling straps having extremities secured to the plate through said openings.
